UNITED STATES PATENT OFFICE.

GEORGE H. WILLIAMS, OF MISHAWAKA, INDIANA, ASSIGNOR OF ONE-HALF TO OVID B. SAILORS, OF SOUTH BEND, INDIANA.

BED-CORNER FASTENING.

1,161,177.

Specification of Letters Patent. Patented Nov. 23, 1915.

Application filed January 7, 1915. Serial No. 1,001.

To all whom it may concern:

Be it known that I, GEORGE H. WILLIAMS, a citizen of the United States, residing at Mishawaka, in the county of St. Joseph and 5 State of Indiana, have invented certain new and useful Improvements in Bed-Corner Fastenings, of which the following is a specification.

The invention relates to an improvement 10 in beds, and more particularly to the means for locking the corner posts and side rails of the bed together.

The invention has for its primary object 15 the provision of a bed lock in which the side rails formed of angle iron may be firmly and securely locked to the corner posts without the rail ends being in any way specially fashioned with portions for interlocking purposes, the same simply consisting of a 20 section of angle iron of the proper length, and thereby materially lessening the cost of manufacturing the side rails for metallic beds.

A further object resides in the provision 25 of means mounted on the corner posts of a bed, for receiving the ends of the side rails and clamping the same therein in a manner to effectively lock and hold the parts in a rigid manner.

The invention in the preferred form of 30 details will be described in the following specification, reference being had particularly to the accompanying drawings, in which:

Figure 1 is a perspective view showing 35 portions of a corner post and side rail of a bed embodying my invention, Fig. 2 is a vertical sectional view taken on the line 2-2 of Fig. 1. Fig. 3 is a perspective view showing 40 one part of a clamping device in full lines, and a coöoperating part in dotted lines. Fig. 4 is a perspective view of a clamping block viewed in inverted position. Fig. 5 is an end view of the complete clamping de- 45 vice.

In the drawings 1 represents a section of 50 the corner post of a bed, 2 one terminal of a side rail, and 3 a bracket attached to the corner post in any suitable manner, and as each 55 bed corner will be similarly formed, it is considered sufficient for the purpose of clearly disclosing the present invention, to illustrate and describe a single bed corner and its coöperating parts only.

The bracket 3 may be attached to the cor-

ner post in any suitable manner, as by means of a bolt 4 passed through the closed end wall thereof and through the corner post, a nut 5 securing the bolt in place. The bracket consists of a hollow casting substantially 60 rectangular in formation with the exception of one end thereof, which is closed as at 6, and of concave formation to fit the tubular formation of the corner post. The end 7 of the bracket is open so as to provide in effect 65 a socket for the reception of the rail end 2, which is preferably of angle iron, and of a dimension in cross section so as to snugly fit within the socket and thereby be held against movement in any direction except in 70 an endwise direction.

In order to hold the side rail against separation from the bracket, I employ a wedging device 8 which is insertible into the socket of the bracket and operable to force 75 the rail end into frictional binding contact with the side and bottom walls 9 and 10 of the bracket. The wedging device comprises what I preferably term a wedge-block 11, having a rectangular head portion 12, and 80 an angular portion 13, the relative angular parts 14 of which converge in the direction of their outer meeting ends, and the edges of which are beveled in a diagonal and in the same plane, as indicated at 14'-14' in Fig. 85

3. Adapted to ride upon the beveled edges of the wedge-block is a binding block 15, which is rectangular in formation with the exception of one corner thereof, as indicated 90 at 16, which is cut away in a plane diagonally of the length thereof, so that one end of the block will be larger than the other, the binding block resting upon the wedge block with the large and small ends of both disposed in opposite directions. The binding 95 block 15 is provided with a screw-threaded bore 17, adapted to receive a screw-threaded bolt 18, and having a head 19 from which extend ears 20 for manipulating the same by hand. The bolt 18 passes through an 100 elongated slot 21 in the head portion 12 of the wedge-block, so as to permit lateral play thereof. By manipulation of the bolt 18, the binding block will be given a combined longitudinal and lateral movement, bringing 105 the same in contact with the upper wall 22 and side wall 23 of the bracket, and, due to the resistance of said walls, exert stress through the wedge-block in a lateral and diagonal direction against the surfaces 24 and 110

25 of the side rail, and thus firmly wedging the latter against endwise movement. By retracting the binding block the side rail may be easily and quickly removed. Also 5 the side rail may be turned so as to present a side surface uppermost and locked in such position in the same manner as above described, as will be obvious.

What is claimed is:—

- 10 1. A bed corner lock for the side rails of a bed, comprising a socketed member adapted to receive the rail end within the socket, and means operable within the socket and adapted for expansive adjustment to effect 15 a binding engagement between said means, the socketed member, and rail end.
2. A bed corner lock for the side rails of a bed, comprising a socketed member adapted to receive the rail end within the socket.
- 20 coöperating wedge-shaped elements within the socket having opposing tapered surfaces, and means for drawing said elements to-

gether to effect a relative lateral movement thereof, whereby said elements, the socketed member, and the rail end will be brought 25 into frictional binding engagement with each other.

3. A bed having corner posts and side rails, comprising a socketed member adapted to receive the rail end within said socket, 30 a wedge-block within said socket, a binding block carried by the wedge-block, and means for adjusting the binding block to cause the same to have a combined longitudinal and lateral movement, whereby to force the rail 35 end into binding engagement with the side walls of the socket member.

In testimony whereof I affix my signature in presence of two witnesses.

GEORGE H. WILLIAMS.
